UNITED STATES PATENT OFFICE.

HENRY SHELDEN GERMOND, JR., OF BAYONNE, AND FRANK L. EIDMANN, OF NORTH BERGEN, NEW JERSEY, ASSIGNEES TO SAID HENRY S. GERMOND, JR.

ELEVATING TRUCK.

Application filed October 4, 1923. Serial No. 666,441.

This invention relates in general to elevating trucks of the type including a main frame mounted on wheels and adapted to be moved about and steered by a draft handle and pushed beneath a load which is to be transported, said main frame carrying an elevating platform adapted to be raised by swinging of the draft handle in a vertical plane to elevate the load from the floor. 5
More particularly, the invention relates to that type of elevating trucks including a member movable substantially vertically in or parallel to the axis of swivel of the steering wheels, said member being adapted to 10 be so connected to the draft handle as to elevate the platform by swinging of the handle in vertical planes with the handle in any of the usual steering positions at angles to the longitudinal median line of the 15 truck.

One object of the invention is to provide a truck of the character described embodying a novel and improved actuating mechanism for raising said platform by means 20 of said draft handle including a member vertically movable substantially in the line of axis of the steering swivel and connected to said elevating platform, and means for connecting said draft handle to said vertically movable member while said handle is 25 in any usual steering position for raising said platform.

Another object is to provide in such a truck novel and improved means for automatically disconnecting the draft handle 30 from operative relation to the said vertically movable member and elevating platform after the platform has been raised to its maximum height, by a longitudinal pull 35 upon the handle such as would be incident to drawing the truck, whereby the possibility of the handle being accidentally thrown upwardly by the descent of the platform is obviated.

A further object is to provide novel and improved means for preventing accidental upward swinging of the handle after the load has been elevated and before the handle has been disconnected from the elevating 40 platform.

Other objects are to provide an elevating truck of the general character described including a member connected to the elevating platform and vertically movable in the

line of axis of the steering swivel and formed 55 with a substantially horizontal segmental flange adapted to be engaged by one end of a thrust pawl pivotally connected to one end of a lever pivoted on a horizontal axis intermediate its ends on said swivel, the 60 other end of said lever being adapted to separably connect with the draft handle pivotally connected to said swivel on said pivot of said lever, whereby said lever may be oscillated about its pivot by said handle 65 simultaneously with swinging of the latter about said pivot to raise the elevating platform and be disconnected from said handle after said platform has been raised, and to obtain other results and advantages as 70 may be brought out by the following description.

Referring to the accompanying drawings, in which the same reference characters designate corresponding and like parts, 75

Figure 1 is a partial sectional and partial side elevational view of an elevating truck embodying our invention, the elevating platform being shown in its lowermost and normal position;

Figure 2 is a top plan view of the truck; 80
Figure 3 is a side elevation of the truck with the platform in its uppermost position and the draft handle shown at the end of its elevating operation;

Figure 4 is a view similar to Figure 3 showing the draft handle in the position assumed when it is utilized for drawing the truck from point to point, the platform actuating mechanism being shown in inoperative position;

Figure 5 is a view similar to Figure 4 showing the manner of releasing the elevating platform to its lowermost position;

Figure 6 is a fragmentary side elevation 90 of the forward portion of the truck showing the operation of the draft handle into the position to elevate the platform, and

Figure 7 is a front elevation of the forward end of the truck showing the manner of operating the elevating mechanism at different steering positions of the draft handle.

In the specific embodiment of the invention shown on the drawings, the reference character A designates the frame of the truck which may be of any suitable construction and is mounted at the rear end on

wheels 1 journaled on a transverse shaft 2 (see Fig. 5). The forward end of the frame A is provided substantially centrally of its width with a king pin 3 revolvably journaled 5 in the frame and carrying at its lower end a pair of steering wheels 4, this construction enabling the truck to be steered by rotation of the king pin 3.

An elevating and load sustaining platform B is mounted on the frame A in such a manner that the truck may be pushed beneath a load which is spaced from the floor as by means of skids, the said platform being adapted to be elevated on the frame A 10 to raise the load from the floor onto the truck. Any suitable means may be utilized for so mounting the platform on the frame, but in the present instance a pair of parallel links 5 is shown as pivotally connected between the frame A and the platform B at each end so that forward motion of the platform causes oscillation of the parallel links 5 which in turn raises the platform on the main frame. All of the above-men- 15 tioned construction is old and well known, and no claim to novelty is based thereon.

Our invention is particularly directed to improved means for raising the elevating platform B by means of a draft handle 30 which is utilized for drawing the truck from place to place. A bracket 6 is rigidly connected to the king pin 3 and projects forwardly and downwardly, as clearly shown in Figure 1, the lower end of said bracket being bifurcated and having pivotally connected between its arms on a horizontal pivot pin 7 a steering and draft handle 8 the pivoted end of which is also bifurcated and provided with substantially longitudinal 35 slots 9 in its arms which receive the pin 7. The free end of the handle 8 may be provided with hand-holds 10 to be grasped by an operator for pulling the truck from place to place, and with this construction it will be 40 obvious that a pull upon the handle 8 will through the bracket 6 serve to draw the truck, and at the same time horizontal swinging of the handle will rotate the king pin 3 and the steering wheels 4 so as to steer 45 the truck.

A sleeve 11 is slidably mounted on the king pin 3 above the frame A and is provided at its upper end with a substantially semi-circular flange 12. The rear side of 50 said sleeve is provided with a longitudinal slot 13 which is connected by a pivot pin 14 to one end of a link 15 the other end of which is pivotally connected by a shaft 16 to the forward end of the platform B. The length 55 of said slot 13 is substantially equal to the distance of vertical movement of the platform B. The sleeve 11 normally rests upon the top of the frame A and when the platform B is in its lowermost position the pivot pin 14 is disposed in the lower end of said

slot. Obviously, when the sleeve 11 is raised upwardly on the king pin 3 the platform B will be pulled forwardly and through the parallel links 5 raised from the frame A.

A lever 17 is pivotally mounted intermediate its ends on the pivot pin 7 and disposed between the arms of the bifurcated end of the handle 8. The inner end of said lever has pivotally connected thereto a thrust pawl 18 which normally underlies and 70 engages the flange 12 of the sleeve 11. The other end of said lever 17 is provided with a head 19 adapted to cooperate with a tooth or lug 20 formed at the base of the bifurcation of the handle 8 so as to interlock the 75 said handle with said lever and cause the lever to swing about its pivot simultaneously with downward swinging of the handle 8 in vertical planes. It will be observed that the sleeve 11 is non-rotatable due to the connection with the link 15, and that the thrust pawl 18 may slide under the flange 12 as the handle 8 is swung in horizontal planes to rotate the king pin 3. Thus, the thrust pawl 18 is in position to engage the flange 80 12 of the sleeve 11 in all of the usual steering positions of the handle 8 at angles to the longitudinal median line of the truck. With the handle 8 interlocked with the lever 17, when the handle is swung downwardly 85 about the pivot 7, the lever 17 is caused to move therewith so that the thrust pawl 18 is raised. An upward thrust is thus imposed upon the sleeve 11 which moves the same upwardly on the king pin 3 so as to 90 elevate the platform B, the positions of the handle, the lever 17 and the sleeve 11 when the platform is raised being shown in Figure 3.

Any suitable means for retaining the platform in its elevated position may be utilized, but in the present instance we have shown the forward end of the platform provided with a rearwardly facing tooth or lug 21 which is adapted to be engaged by one end of a detent lever 22 pivotally mounted intermediate its ends on the frame as at 23. The detent 22 is normally forced into position to engage the lug 21 as the platform is raised, by means of a spring 24. Thus, when the 105 platform reaches its uppermost position the detent lever 22 rides over the lug 21 and engages with the rearward face thereof to hold the platform against downward movement.

It is a feature of the invention that after the platform has been raised to its uppermost position the steering handle 8 is automatically disconnected from the platform by a pull upon the handle such as would be incident to drawing the truck, so that the possibility of the handle being accidentally forcibly thrown upward should the platform B be accidentally released, is obviated. This function is accomplished through the 110 pin and slot connection 9 of the handle with 115 120 125 130

the pivot pin 7. When a pull is exerted upon the handle, the handle slides forwardly on the pin 7 so as to disengage the lug 20 from the head 19 of the lever 17 thereby disconnecting said lever from the handle and permitting the lever, by action of gravity on the sleeve 11, to swing upwardly to its normal inoperative position, as shown in Figure 5. When the lever 17 is so released the sleeve 11 slides downwardly on the king pin 3 whereby the pivot pin 14 of the link 15 is positioned in the upper end of the slot 13, so that should the platform B then be released the pin 14 would slide downwardly in the slot 13 without any effect upon the lever 17.

It is also important that means be provided for preventing injury to an operator by upward swinging of the handle incident to descent of the platform should the truck be left with the platform elevated and a load thereon without disconnection of the handle from the lever 17. Thus, we provide a detent 25 having one end pivotally connected at 26 to the bracket 6 and the other end adapted to fall by action of gravity into engagement with a lug 27 provided on the handle 8. When the handle is swung downwardly to elevate the platform B, the detent 25 follows the handle until the latter reaches its lowermost position when the detent falls behind the lug 27, as shown in Figure 3, whereby upward movement of the handle is prevented. A spring 28 may be secured to the detent 25 to engage the bracket 6 for initiating movement of the detent 25 into its operative position when the handle 8 is swung downwardly.

Obviously, the platform B may be released from its elevated position by oscillation of the detent lever 22 to disengage it from the lug 21. Means is preferably provided for convenient actuation of said detent lever when the operator is standing in any of the usual steering positions relative to the truck, and such means is shown as comprising a substantially semi-circular treadle 29 arranged at the forward side of the sleeve 11 and overlying the operating end of the detent lever 22, said treadle being preferably pivoted to the frame A on the same axis as the lever 22. Thus, downward pressure on the treadle 29 by the foot of the operator, as shown in Figure 5, will disengage the detent lever 22 from the lug 21 and permit descent of the platform.

To prevent accidental or unintentional actuation of the treadle 29 when the handle is operatively connected to the lever 17, the handle may be provided with arms 31 adapted to underlie the treadle 29 when the handle is in its lowermost position as shown in Figure 3. It will be observed that there are three safety features of the truck which prevent the possibility of injury to an operator by upward swinging of the handle on acci-

dental descent of the platform, namely, the automatic disconnection of the handle from the lever 17 when the handle is pulled forwardly, the detent 25, and the arms 31 to underlie the treadle 29.

Any known means may be utilized for retarding the descent of the platform, and in the present instance we have shown the usual cylinder and piston construction 30, the piston being pivotally connected to the platform B and one end of the cylinder pivotally connected to the frame A.

In the operation of the truck, assuming the platform in its lowermost position, the lever 17 will be swung upwardly into the position shown in Figure 1. When it is desired to raise the platform B the handle 8 is swung upwardly about its pivot 7, as indicated by Figure 6, until the lug 20 on the handle engages the head 19 of the lever.

The head of the lever is preferably formed with an approach cam 32 over which the lug 20 is adapted to ride, said approach cam automatically lifting and guiding the handle over the head 19, lifting action being permitted by the pin and slot connection 7, 9. It will be noted that this connection of the handle 8 with the lever 17 can take place at any of the usual steering positions of the handle, as clearly shown in Figure 7, in which the action is shown as taking place at two positions substantially 180° apart.

When the handle has been so connected to the lever 17, the handle is swung downwardly, as shown in Figure 3, whereby the platform is elevated as above described.

The handle 8 and the lever 17 in effect form a two-part handle, one of said parts being fulcrumed to the steering swivel comprising the king pin 3 to swing in a vertical plane and capable of movement with said swivel about the sleeve 11, while the other part, the handle 8, is adapted to be interlocked with the first-mentioned part when swung downwardly in a vertical plane and actuate said first-mentioned part about the fulcrum to elevate the platform.

While we have shown and described an elevating truck embodying certain preferred details of construction, it will be understood that this is mainly for the purpose of illustrating the principles of the invention, and that many modifications and changes can be made in the said details without departing from the spirit or scope of the invention. Therefore, we do not desire to be understood as limiting ourselves except as required by the following claims when construed in the light of the prior art.

Having thus described the invention, what we claim is:

1. An elevating truck comprising a main frame mounted on wheels at its rear end, a steering swivel carrying wheels journaled in the front end of said frame, a member mov-

able in substantially the line of axis of said steering swivel and having a peripheral flange, an elevating platform mounted on said frame for vertical movement, an operative connection between said member and said platform, an articulated two-part handle for actuating said member, one part of said handle being fulcrumed intermediate its ends on said steering swivel to swing in vertical planes, while the other part is adapted to interlock with the first-mentioned part as the second-mentioned part is swung downwardly in a vertical plane to actuate said first-mentioned part, and a thrust pawl interposed between said first-mentioned part and said flange to raise said member as said first-mentioned part is actuated and elevate said platform.

2. An elevating truck comprising a main frame mounted on wheels at its rear end, a steering swivel carrying wheels journaled in the front end of said frame, a member movable in substantially the line of axis of said steering swivel and having a peripheral flange, an elevating platform mounted on said frame for vertical movement, an operative connection between said member and said platform, a lever pivoted intermediate its ends on said steering swivel to swing in vertical planes, a thrust pawl interposed between one end of said lever and said flange on said member, and a draft handle pivotally mounted on said steering swivel and adapted to interlock with said lever as the handle is swung downwardly to actuate said lever and raise said member to elevate said platform.

3. An elevating truck comprising a main frame mounted on wheels at its rear end, a steering swivel carrying wheels journaled in the front end of said frame, a member movable in substantially the line of axis of said steering swivel and having a peripheral flange, an elevating platform mounted on said frame for vertical movement, an operative connection between said member and said platform, a lever pivoted intermediate its ends on said steering swivel to swing in vertical planes, a thrust pawl interposed between one end of said lever and said flange on said member, and a draft handle pivotally mounted on said steering swivel coaxially with said lever and adapted to interlock with said lever as the handle is swung downwardly to actuate said lever and raise said member to elevate said platform.

4. An elevating truck comprising a main frame mounted on wheels at its rear end, a steering swivel carrying wheel journaled in the front end of said frame, a member movable in substantially the line of axis of said steering swivel and having a peripheral flange, an elevating platform mounted on said frame for vertical movement, an operative connection between said member and said platform, a lever pivoted intermediate

its ends on said steering swivel to swing in vertical planes, a thrust pawl interposed between one end of said lever and said flange on said member, and a draft handle pivotally mounted on said steering swivel and adapted to interlock with said lever as the handle is swung downwardly to actuate said lever and raise said member to elevate said platform, the pivotal connection of said handle permitting relative movement of said handle and said lever to disconnect said handle from said lever by a longitudinal pull upon the handle.

5. An elevating truck comprising a main frame mounted on wheels at its rear end, a steering swivel carrying wheels journaled in the front end of said frame, a member movable in substantially the line of axis of said steering swivel and having a peripheral flange, an elevating platform mounted on said frame for vertical movement, an operative connection between said member and said platform, a lever pivoted intermediate its ends on said steering swivel to swing in vertical planes, a thrust pawl interposed between one end of said lever and said flange on said member, a draft handle having a pin and slot connection with said swivel for longitudinal movement and pivotal movement in vertical planes, and means for causing interlocking of said handle and said lever as the handle is swung downwardly, said interlock between the handle and said lever being released by a longitudinal pull upon said handle.

6. The elevating truck set forth in claim 5 in which said pin and slot connection of the handle is with the same pivot which supports said lever.

7. An elevating truck comprising a main frame mounted on wheels at its rear end, a steering swivel carrying wheels journaled in the front end of said frame, a member movable in substantially the line of axis of said steering swivel, an elevating platform mounted on said frame for vertical movement, an operative connection between said member and said platform, a handle pivotally connected to said steering swivel to swing in a vertical plane, said handle being bifurcated adjacent its pivot and formed with a lug at the base of the bifurcation, a lever pivotally mounted between its ends on said pivot of the handle between the arms of said bifurcations, one end of said lever being formed to interlock with said lug on the handle as the handle is swung downwardly to actuate the lever, and an operative connection between the other end of said lever and said member to raise the latter and elevate the platform as said lever is actuated.

8. An elevating truck comprising a main frame mounted on wheels at its rear end, a steering swivel carrying wheels journaled in

the front end of said frame, a platform mounted on said frame for vertical movement, a handle pivotally mounted on said steering swivel to swing in a vertical plane, means for connecting said handle to said platform to raise the latter as said handle is swung downwardly, and means adapted to be interposed between said swivel and said handle between the free end of the handle and the pivotal connection thereof to said swivel for holding said handle against upward movement while the handle is operatively connected to said platform.

9. An elevating truck comprising a main frame mounted on wheels at its rear end, a steering swivel, carrying wheels journaled in the front end of said frame, a platform mounted on said frame for vertical movement, a handle pivotally mounted on said steering swivel to swing in a vertical plane, means for connecting said handle to said platform to raise the latter as said handle is swung downwardly, and a detent connected to said frame and adapted to engage said handle when the latter is in its lowermost lifting position to hold the handle against upward movement while the same is operatively connected to the platform.

10. An elevating truck comprising a main frame mounted on wheels at its rear end, a steering swivel carrying wheels journaled in the front end of said frame, a platform mounted on said frame for vertical movement, a handle pivotally mounted on said steering swivel to swing in a vertical plane, means for connecting said handle to said platform when the handle is in any steering position to raise said platform as the handle is swung downwardly, and a detent mounted on said swivel to engage said handle in any of said steering positions at its lowermost lifting position to hold said handle against upward movement.

11. An elevating truck comprising a main frame mounted on wheels at its rear end, a steering swivel carrying wheels journaled in the front end of said frame, a platform mounted on said frame for vertical movement, a handle pivotally mounted on said steering swivel to swing in a vertical plane and having a lug thereon, means for connecting said handle to said platform to raise the latter as the handle is swung downwardly, and a detent pivotally mounted at one end on said frame with its other end adapted to follow said handle as the same is swung downwardly and engage said lug when the handle reaches its lowermost lifting position to hold the handle against upward movement.

12. An elevating truck comprising a main frame mounted on wheels at its rear end, a steering swivel carrying wheels journaled in the front end of said frame, a platform mounted on said frame for vertical move-

ment, a member movable in substantially the line of axis of said steering swivel and having a pin and slot connection with said platform whereby said member and said platform are capable of relative movement a distance substantially equal to the distance of movement of said platform, a handle mounted on said swivel to swing in a vertical plane, and means connected to said member and adapted to separably interlock with said handle as the latter is swung downwardly to raise said member and elevate said platform, said handle and means being separable after said platform has been elevated and permitting said member and said means to return to their normal inoperative positions, whereby subsequent descent of said platform takes place independent of said member.

13. An elevating truck comprising a main frame mounted on wheels at its rear end, a steering swivel carrying wheels journaled in the front end of said frame, a platform mounted on said frame for vertical movement, a member movable in substantially the line of axis of said swivel, a link having a pivotal connection at one end with said platform and a pin and slot connection at the other end with said member to permit relative movement of said member and said link a distance substantially equal to the distance of movement of said platform, a handle pivotally mounted on said swivel to swing in a vertical plane, and means connected to said member and adapted to separably interlock with said handle as the latter is swung downwardly to elevate said platform, said handle and said means being separable after elevation of said platform to permit said member and said means to return to their normal inoperative positions.

14. An elevating truck comprising a main frame mounted on wheels at its rear end, a steering swivel carrying wheels journaled in the front end of said frame, a platform mounted on said frame for vertical movement, a member movable in substantially the line of axis of said swivel and having a longitudinal slot of a length substantially equal to the distance of movement of said platform, a link pivotally connected at one end to said platform, a pin passing through said slot and the other end of said link to connect said link to said member, a handle pivotally connected to said swivel to swing in vertical planes, and means connected to said member and adapted to separably interlock with said handle as the latter is swung downwardly to elevate said platform, said handle and said means being separable after elevation of said platform.

15. An elevating truck comprising a main frame mounted on wheels at its rear end, a steering swivel carrying wheels journaled in the front end of said frame, a platform

mounted on said frame for vertical movement, a member movable in substantially the line of axis of said swivel and having a longitudinal slot of a length substantially equal to the distance of movement of said platform, a link pivotally connected at one end to said platform, a pin passing through said slot and the other end of said link to connect said link to said member, a handle 10 having a pin and slot connection with said swivel for longitudinal movement and for pivotal movement in vertical planes, a lever pivotally mounted intermediate its ends on

the pivot of said handle and adapted to separably interlock at one end with said handle as the latter is swung downwardly, and a thrust pawl pivotally connected at one end to the other end of said lever and engaging said member to raise the same as said handle is swung downwardly and elevate the 20 platform, said handle and said lever being adapted to be separated by a longitudinal pull upon the handle.

HENRY SHELDEN GERMOND, JR.
FRANK L. EIDMANN.
